UNITED STATES PATENT OFFICE.

CALVIN JACKSON, OF JACKSONWALD, PENNSYLVANIA, ASSIGNOR TO HENRY S. HALTZEL, OF ALLENTEWON, PENNSYLVANIA.

KNOCKDOWN SUPPORT.

Application filed April 19, 1923. Serial No. 633,299.

To all whom it may concern:

Be it known that I, CALVIN JACKSON, a citizen of the United States, residing at Jacksonwald, in the county of Berks and State of Pennsylvania, have invented certain new and useful Improvements in Knockdown Supports, of which the following is a specification.

This invention relates to improvements 10 in knockdown supports and the object in the present invention is to provide a simple device to be used as a support for washing machine tubs or like articles.

The invention consists of two pairs of 15 clamping members, one pair of which is intended to engage and hold the legs and the other pair to engage and hold a series of lateral bars on which the object to be supported will rest.

20 The entire set of four clamping members are held together by means of a single bolt, centrally disposed, so that the loosening of the nut on said bolt will permit the removal of the legs and the arms, to the end 25 that the device may be easily packed for shipping, and easily and quickly assembled and set up for use.

The invention is more fully described in the following specification and clearly illustrated in the accompanying drawing, in 30 which:—

Figure 1 is a plan view and Figure 2 a side elevational view of my device, assembled.

35 Figure 3 is an enlarged plan view thereof, with the arms and legs broken away, and Figure 4 is a central sectional view taken through line 3—3 of Figure 3.

The numeral 1 designates the lower, and 40 2 the upper member of the leg clamp. These members are each formed with a series, preferably three, of half round, downwardly projecting jaws 3, each pair of jaws forming a receptacle for the inner 45 end of one of the legs 4.

The numeral 5 designates the lower, and 50 6 the upper member of the arm clamp. These members are each formed with a series of radiating grooves 7, and engaging these grooves, between the upper and lower clamp member, is the inner end of one of the supporting arms 8.

55 Each member of the two clamping sets, 1, 2, 5 and 6, is provided with a central opening and a bolt 9 passes through the

openings, has its head embedded in a depression 12 in the upper surface of the member 6, to form a flush upper surface therefor, and a nut 13 on its lower extremity, whereby, the tightening of the nut on the bolt will draw the members 1, 2, 5 and 6 together, and effectively secure both the series of leg members 4 and the arms 8 in position.

The upper edge of the leg clamp member 2 is formed with a series of slight depressions 11, in each of which one of the radiating grooved portions 7 of the clamp member 5 will rest, and, when the parts are drawn together as above described, this will prevent rotation as between the arm clamp and the leg clamp members.

It is evident that a very slight loosening of the nut 13 will permit both the leg and arm clamping members to open sufficiently 75 to allow the withdrawal of the legs and arms, and permit a compact parcel to be made of the entire device.

It is also evident that the support may be used for other purposes than that of supporting a washing machine tub, and that the number of legs and arms may be varied to suit circumstances.

Having thus fully described my invention, what I claim is:—

1. In a knockdown support, a pair of leg clamping members provided with leg engaging jaws, a pair of arm clamping members provided with arm engaging grooves, each member having a central opening, a series of depressions in one of the leg clamping members adapted for engagement by one of the arm clamping members and a single bolt passing through the central openings and capable of securing the leg and arm clamping members together.

2. In a device of the character described, a two-piece leg clamp provided with leg openings, a two-piece arm clamp provided with arm engaging means, depressions in one of the leg clamping members adapted for engagement by one of the arm clamping members to prevent independent rotation, and a single bolt capable of drawing both the leg and the arm clamping members together.

In testimony whereof I affix my signature.

CALVIN JACKSON.
